(57) **CLAIM**

The ornamental design for a motorcycle saddlebag light as shown and described.

DESCRIPTION

FIG. 1 is a perspective view of the motorcycle saddlebag light.

FIG. 2 is a front elevational view thereof.

FIG. 3 is a rear elevational view thereof.

FIG. 4 is a first side view thereof.

FIG. 5 is a second side view thereof, opposite the first side view.

FIG. 6 is a top side view thereof; and,

FIG. 7 is a bottom side view thereof.

The rear surface of the motorcycle saddlebag light shown in broken lines form no part of the claimed design.
